UNITED STATES PATENT OFFICE.

GEORGE ALFRED JACKSON, OF WALTHAM, MASSACHUSETTS, ASSIGNEE TO THE SAME-WELL FIRE ALARM TELEGRAPH COMPANY, OF NEW YORK, N. Y., A CORPORATION OF NEW YORK.

ATTACHMENT FOR SIGNAL BOXES.

Application filed December 27, 1922. Serial No. 609,250.

To all whom it may concern:

Be it known that I, GEORGE ALFRED JACKSON, a citizen of the United States, residing at Waltham, county of Middlesex, and Commonwealth of Massachusetts, have invented certain new and useful Improvements in Attachments for Signal Boxes, of which the following is a specification.

This invention relates to attachments for signal boxes; and is particularly suited for use in connection with emergency signaling boxes such, for example, as those ordinarily termed "fire alarm boxes."

Fire alarm boxes now in general use, particularly those forming part of municipal fire alarm systems,—comprise a clock-work train, which is enclosed in a substantially round inner case; a square intermediate case containing said train and its case, together with a terminal block, a telegraph key and an audible signaling device; and an outer case in which said square intermediate case is, in turn, enclosed. The round inner case has a cover and the square intermediate case has a door, openings being provided in both said cover and said door through which extends a starting lever whereby the clockwork may be set in motion without opening said door. The outer case is also provided with a door, arranged to protect the starting lever and intermediate case from exposure to the weather, besides tending to discourage mischievous tampering with the starting lever.

During the early introduction of fire alarm signal boxes, trap locks were generally provided for the outer doors thereof, keys being given responsible persons, and such keys being marked for identification so that when a box had been opened, the key (being trapped in the lock) identified the holder of such key. This method caused disastrous delays, when key holders were not quickly found at times when signals should be transmitted, and the utilization of other expedients has therefore been undertaken, the most widely used of which consists of a permanently attached key or handle for opening the outer door, together with a housing or guard for such key or handle, which guard has a frangible panel to be broken to afford access to the key or handle. All such prior arrangements required an extended series of acts preliminary to obtaining access to the

starting lever, and this fact led to failures to transmit intended signals, resulting from the concealment of the starting lever at all times other than the brief intervals when the outer door was open for the transmission of a signal, so that those having occasion to send signals have repeatedly overlooked actuation of the handle after having performed one or more of the acts preliminary to obtaining access thereto. Furthermore, the use of frangible guards has introduced a hazard of injury to users of such boxes, because jagged pieces of a broken frangible panel often find lodgment in such positions as to produce lacerations of the fingers of users. Attempts have been made to overcome the latter defect by providing a hinged cover, to be released by breaking the frangible panel, with a view of carrying away dangerous fragments of a broken panel; but the use of such an arrangement has nevertheless been attended with injuries to users, partly because a jagged piece of broken glass sometimes finds such lodgment around keys or handles as not to be carried away by the swing of the cover, and partly because such devices are so rarely operated that the hinges thereof become clogged by paint and rust, so that they fail to function when needed.

When such hinged guards are in working order, they have the further disadvantage of affording an enticing target for mischievous boys; and, once the frangible panel is broken, the hinged cover cannot be caused to remain closed until a new frangible panel has been inserted in same. This fact has repeatedly contributed to the transmission of false signals between the time when a police officer has found the cover open and the time when an inspector summoned by such officer has arrived to replace the frangible panel. In a number of instances, investigation has disclosed that such false signals have been transmitted because passers-by, thinking that the box was out of service because the guard cover was open, and wishing to avail themselves of the opportunity thus apparently afforded to harmlessly learn how to send an alarm, have opened the outer door and experimented with the starting lever, without intending to cause the transmission of a signal.

It is well known that when persons have occasion to cause the transmission of an

emergency signal, they are usually laboring under a degree of excitement which precludes their comprehending and intelligently acting upon printed instructions, and which 5 frequently prevents them from sensing the presence of an object such as a starting lever which they have never seen, much less sensing the necessity for operating it. This is especially true at night, when the box may 10 be in a shadow, so that neither the starting lever nor the lettering of the instructions may be discernible. On the other hand, where both the starting lever and the instructions associated therewith are continuously exposed to observation, it has been found that passers-by will familiarize themselves with the method of sending a signal so that, when occasion arises, they will know the location of the starting lever and understand that it must be actuated. 20

It has also been found that, when the starting lever is thus exposed, and it is clearly indicated that actuation thereof will cause the transmission of a signal, mischievous boys are less likely to use, as a target, a transparent panel which covers the starting lever, and inquisitive persons are enabled to satisfy their curiosity without actually handling the starting lever. As a result, it 25 has been found that when the starting lever is thus constantly exposed to view, although protected from chance of accidental operation thereof, false signals are limited to those instances in which the person sending the 30 signal does so with deliberation. It is obvious that, if it is to be possible for any passer-by to expeditiously send an emergency signal from any such box in case of need, facilities provided for so doing will 35 also enable any passer-by to maliciously send a false signal; as no means are now known for enabling mechanism to discriminate, in responding to manual actuation thereof, with reference to the motives of 40 the operator.

It has heretofore been suggested that glass panels be mounted in the outer doors of fire alarm boxes, such doors having openings provided therefor which are positioned to 45 afford a view of the clock work starting levers therethrough and so as to afford access to such levers when the glass panels have been broken therefrom. Although the advantages of such an arrangement have been readily conceded, in principle, adoption thereof for general use in the forms heretofore suggested and tried has been effectively opposed on the ground that the breaking of the glass panel has so exposed the door of 50 the inner case to the elements that rain and sleet have driven in and, working through the opening around the starting lever and the spaces between the inner case and its door, have impaired or destroyed the operability of the box mechanism; and upon the

further ground that, as the user must insert his hand through such an opening, for a considerable distance, in order to reach the end of the starting lever which projects through the inner door, danger of injury 70 from pieces of broken glass is much greater than that incident to the use of conventional glass key guards.

A further defect has developed, incident to attempts to utilize such prior glass panel 75 pull-lever-guards, in that the users have been found to frequently employ considerable force in breaking the glass, often striking same with a large stone or other heavy object, and employing such force as to break 80 or otherwise disable the starting lever, and—in extreme cases—to ruin the clock-work mechanism; as the starting levers of nearly all boxes now in use are comparatively frail, and are supported by the frame 85 of the clockwork.

It has been suggested that the present construction and arrangement of starting levers and inner case doors should be revised, with a view of at least partially overcoming such 90 defects, but the expense and inconvenience of such a course has been deemed prohibitive in the instance of the large number of existing boxes, because of the impracticability of making needful structural changes without returning the boxes to the factory and virtually rebuilding them. Should the rebuilding of the boxes of any system be so undertaken, it would be needful to provide and install a complete set of temporary boxes 95 while the existing boxes were removed for rebuilding, because the various boxes in each system bear different code numbers and are specially speeded for their respective numbers, so that given individual temporary 100 boxes could be used in but one location, and each existing box could, after rebuilding, only be installed in its original location, unless further expense were incurred for changing the code numbers and for respeeding. 105

Although such a revision of structure and arrangement might be incorporated in new boxes, so doing would be highly undesirable for the reason that many of the parts of such 110 boxes which are most likely to need emergency replacement would not, in the event of such revision, be available for interchangeable use in both existing boxes and such revised boxes.

An important object of this invention is to provide an attachment for a signal box having a manually operable member, which attachment will normally serve to protect such member from exposure both to the 115 weather and to accidental actuation; while affording a clear view thereof, so that passers-by may become familiar with the appearance and mode of operating same, besides enabling access to such member to be 120

expeditiously obtained with a maximum of simplicity and without exposing the user to danger of injury.

Another object is to provide, in such an attachment, construction and arrangement whereby the removal of the normal protection to the manually operable member will not expose the inner door or the clockwork starting lever projecting therethrough to 10 injury from the weather or to tampering by those maliciously inclined.

Another object is to provide such an attachment which—after opening thereof to afford access to the manually operable member—may be readily again secured in closed position, so as to renew protection of such member from the weather and from accidental actuation thereof.

A further object is to provide such an attachment which may be embodied in a unitary structure with an outer door for signal boxes, of such form as to be available for ready application to one or another of the forms of municipal fire alarm boxes now in 25 most general use, without material alteration of either the guard or door structure or of the box itself (other than the substitution of one door structure for another).

A still further object is to provide, in such an attachment, construction and arrangement of parts whereby the application of violence to the manually operable member associated therewith will be unlikely to disable such member, and will not, in any event, 35 cause injury to or disablement of the clockwork or its starting lever.

Other objects are to provide such an attachment which may be economically manufactured, which is readily adapted for utilization with either existing or new boxes, and which is durable and dependable in 40 operation.

Still other objects will in part be obvious and are in part hereinafter set forth in 45 greater detail.

With the aforesaid objects in view, this invention consists in the novel constructions and arrangements of parts hereinafter described in a preferred embodiment thereof, pointed out in the annexed claims, and 50 illustrated in the accompanying drawing, in which like parts are designated by the same reference characters throughout the several views, and in which

55 Figure 1 is a front view of a signal box provided with an attachment constructed in accordance with this invention;

Fig. 2 is a rear view of the door of Fig. 1;

Fig. 3 is a vertical section taken on the 60 line 3—3 of Fig. 2; and

Fig. 4 is a horizontal fragmentary section, taken on the line 4—4 of Fig. 1.

Referring to Fig. 1,—the door 21 is mounted upon the signal box outer case 22; 65 being secured thereto by means of the hinges

23, 23, and being normally held in closed position by the lock 24 (see also Fig. 2). Said door has the rearwardly extending portion 25, which portion is so formed as to provide the recess 26 in the front surface 70 of said door; an opening 27 being formed in the rear wall of said portion 25, for a purpose which will be hereinafter more fully explained. Said door also has the forwardly extending portion 28, which portion is so 75 formed as to provide the recess 29.

The actuating arm 30 is pivotally connected at 31 to the rear side of the door 21, for movement in a vertical plane parallel to the surface of said door. The manually operable member or so-called "pull hook" 32 is carried by said arm 30, projects through the opening 27 and extends into the recess 26, so as to enable said hook to be readily grasped for the purpose of imparting movement to the arm 30 from the outer side of the door 21. The portion of the arm 30 adjacent to the hook 32 is so formed as to snugly engage the rear surface of the portion 28 of the door 21, and so that said arm 80 will at all times cover the rear side of the opening 27, regardless of the position of said arm within the maximum range of intended movement permitted the hook 32 by said opening; to the end that rain, snow and sleet 85 will not be permitted to drive around said opening against the inner case door and train starting lever of such signaling mechanism as may be housed behind the door 21, and to the further ends that insects will be 90 unable to enter the outer case through said opening and that maliciously inclined persons will be prevented from inserting any object or implement through said opening 95 in such manner as to injure or disable such signaling mechanism.

The arm 30 is so formed as to provide the ledges 33 and 34, said ledges being respectively so positioned as to be suited for engaging the starting levers of one or another 100 well known type of fire alarm signal box; boxes of such types being so arranged that, were doors such as the door 21 applied thereto, the train starting levers of each of the 105 boxes of one of such types would occupy the position indicated by the dotted outline 110 in Fig. 2, and the corresponding levers of the other of such types of boxes would occupy the position indicated by the dotted outline 115 in Fig. 3.

The lug 37 is carried by the arm 30, and is so formed and positioned as to cooperate with the stops 38 and 39 for the purpose of suitably limiting the travel of the arm 30; the stop 39 being so positioned and of such strength as to successfully resist any attempt to so actuate the arm 30 by means of the hook 32 as to cause injury to any starting lever (such as the levers indicated by either the outline 35 or the outline 35') or to the 120 125 130

clockwork with which such levers may be associated.

The strap 40 passes behind the lug 37 for the purpose of holding the arm 30 against being sprung away from the rear side of the door 21 by pressure applied to said arm through the hook 32.

The spring 41 is so applied as to form yielding means for maintaining the arm 30 in its normal elevated position.

A suitable legend 47 is carried by the door 21 adjacent the pull hook 32, giving instructions for the operation of said hook, and suitable enclosing structure is provided 15 for said hook, its containing recess 26 and the portion of the outer surface of the door 21 which carries said legend 47. Said structure comprises the frame 42, which is hinged at 43, to the door 21, is normally retained 20 in closed position by engagement of the latch spring 44 carried by said door with a latch strike plate 45 carried by said frame, and carries the handle 46 by means of which it may be conveniently opened and closed.

25 The transparent panel 48 is mounted in the frame 42, said panel being secured in grooves 49 in the bottom and side walls of the opening enclosed by said frame (see Figs. 3 and 4). Said panel is so positioned 30 and of such form as to enable the hook 32 and the legend 47 to be readily viewed therethrough.

In accordance with one of the more specific aspects of this invention, the material of the 35 panel 48 should be such as to render it non-frangible in the ordinary sense, to the end that it cannot be so shattered as to be likely to cause fragments thereof to find lodgment where they might injure the hand of anyone 40 having occasion to actuate hook 32. For this purpose, it has been found desirable to employ a transparent variety of a material which, in many respects, is like what is known as "pyralin" or celluloid.

45 In accordance with a broader aspect of this invention, it will be evident that other features thereof may be advantageously employed in connection with a more readily frangible material, such as glass, because it 50 is reasonable to assume that even a glass panel would not ordinarily be broken when a signal was transmitted from a box equipped with an attachment constructed in accordance with this invention, except 55 as to the nonfrangibility of the transparent panel.

The latch spring 44 is secured to the outside of the upper wall of the rearwardly extending portion 25 of the door 21, and 60 the free end of said spring extends into the recess 29 and through the slot 36 in the lower wall of the forwardly extending portion 28, and is so formed as to be disposed in the path of the plate 45 so as to be 65 adapted to engage said plate in a manner

which will yieldingly retain said frame in closed position.

The plate 45 is detachably secured to the upper portion of the rear side of the frame 42, as by the screws 50, 50, in such position 70 as to serve to prevent withdrawal of the panel 48 from said frame.

The ribs 51, 51 are formed in the front surface of the door 21 and adjacent the sides of the frame 42; and the formation of 75 said frame, with reference to said ribs and to the forwardly extending portion 28 of said door, is such as to minimize opportunity for rain to be so driven behind said frame as to reach the hook 32, the arm 30 80 or the inner surface of the door 21.

The legends 52 and 53 carried by the front surfaces of the portion 28 of the door 21 and the handle 46, respectively, give instructions for obtaining access to the hook 32. 85

The plunger 54 is slidably mounted in an opening through the door 21, so positioned that the front end of said plunger may engage the inner surface of the lower portion 90 of the frame 42 for the purpose of imparting an opening tendency thereto. The spring 55 is secured to the door 21, and the free end thereof is so applied to the inner end of said plunger as to urge same toward 95 said frame.

The lugs 56, 56, the abutments 57, 57, 57, 57 and the spring 58 are carried by the rear surface of the door 21, in the lower portion thereof, for the purpose of supporting a reserve supply of panels, such as the 100 panel 48.

In applying this invention to existing signal boxes, it is merely needful to remove the present door and apply in place thereof a suitable door comprising a signal box attachment constructed in accordance with this invention. It is believed that the foregoing description will make obvious to those skilled in this art the manner of embodying this invention in signal boxes in 110 course of manufacture.

The operation of the attachment shown by the drawings and hereinbefore described in detail is as follows:

When it is desired to cause the transmission of a signal, the hinged section of the frame 42 should be swung upon its hinges 43 from its normal closed position, by means of the handle 46, so as to give access to the pull hook 32; and said hook should thereupon be depressed in the usual manner. Said hinged section may then be returned to its closed position, thus restoring its normally effective relationship to the recess 26. If, when it is intended to so return said 125 hinged section, it is not moved to a position which enables the free end of the spring 44 to effectively engage the plate 45, the spring 55 will act through the plunger 54 to swing said hinged section far enough out 130

of a vertical plane so that gravity will cause said section to swing to the position indicated by dotted lines in Fig. 1; thus directing attention to the fact that the structure

5 has not been properly restored. Without this feature, the hinged section might be left in such partly closed position as to admit rain, snow and sleet behind said section in sufficient volume to interfere with the 10 operability of the attachment.

Should it be needful to replace the panel 48, the screws 50, 50 should be withdrawn and the plate 45 should be removed from the frame 42. The previously used panel 15 48, or any remaining parts thereof, may then be taken out of the grooves 49, and a new panel may be inserted in such grooves. After inserting a new panel, as just described, the plate 45 should be again secured 20 in position by means of the screws 50, 50; and the frame may then be restored to its closed position.

Obviously, other structures may be devised which will embody certain or all of 25 the features of this invention. The foregoing detailed description and the accompanying drawings should therefore be considered as illustrative rather than in a limiting sense; and what I claim and desire to 30 secure by Letters Patent of the United States is:

1. In an attachment for a signal box; a manually operable actuating member, a door associated with said member and having 35 a rearwardly extending recessed portion through which is provided an opening for said member, relative construction and arrangement of said member and said door whereby some portion of said member will 40 at all times cover said opening, suitable enclosing structure for said recessed portion, said structure suitably secured to the outer side of said door and comprising a transparent panel so positioned and of such form 45 as to enable said member to be readily viewed therethrough, spring latch mechanism for maintaining said structure in normal effective relationship to said recessed portion, and an operating handle carried 50 by said structure.

2. In an attachment for a signal box; a manually operable actuating member, a door associated with said member and having a rearwardly extending recessed portion 55 through which is provided an opening for said member, relative construction and arrangement of said member and said door whereby some portion of said member will at all times cover said opening, suitable enclosing structure for said recessed portion, said structure suitably secured to the outer side of said door and comprising a nonfrangible transparent panel so positioned and of such form as to enable said member to be 60 readily viewed therethrough, spring latch

mechanism for maintaining said structure in normal effective relationship to said recessed portion, and an operating handle carried by said structure.

3. In an attachment for a signal box; a 70 manually operable actuating member, a door associated with said member and having a rearwardly extending recessed portion through which is provided an opening for said member, relative construction and arrangement of said member and said door whereby some portion of said member will at all times cover said opening, suitable enclosing structure for said recessed portion, said structure hinged to the outer side of 75 said door and comprising a nonfrangible transparent panel so positioned and of such form as to enable said member to be readily viewed therethrough, spring latch mechanism for maintaining said structure in normal effective relationship to said recessed portion, and an operating handle carried by 80 said structure.

4. In an attachment for a signal box; suitable enclosing structure for a manually 85 operable member, means for suitably securing said structure to the outer side of an intended box, a nonfrangible transparent panel carried by said structure and so positioned and of such form as to enable such 90 a member to be readily viewed therethrough, and an operating handle carried by said structure.

5. In an attachment for a signal box; suitable enclosing structure for a manually 100 operable member, said structure comprising a hinged section, spring latch mechanism for maintaining said section in normal closed condition and a handle whereby said hinged section may be readily opened, and a 105 nonfrangible transparent panel carried by said hinged section.

6. In an attachment for a signal box; suitable enclosing structure for a manually 110 operable member, said structure having a rearwardly extending recessed portion through which is provided an opening for a manually operable actuating member, a hinged section, spring latch mechanism for maintaining said section in normal effective relationship to said recessed portion and a handle whereby said hinged section may be readily opened, and a nonfrangible 115 transparent panel carried by said hinged section.

7. In an attachment for a signal box; a door having a rearwardly extending portion through which is provided an opening, an actuating arm pivotally connected to the rear side of said door, said arm so formed 120 and arranged as to be suited for operative engagement with the clockwork starting levers of either of a plurality of types of signal boxes, a manually operable member carried by said arm and projecting for 125 130

wardly through said opening, suitable enclosing structure secured to the outer side of said door, spring latch mechanism for maintaining said structure in normal closed condition, a handle whereby said structure may be readily opened, and a nonfrangible transparent panel carried by said structure and so positioned and of such form as to enable said member to be readily viewed therethrough.

8. In an attachment for a signal box; a door having a rearwardly extending portion through which is provided an opening, an actuating arm pivotally connected to the rear side of said door, said arm so formed and arranged as to be suited for operative engagement with the clockwork starting levers of either of a plurality of types of signal boxes and so that some portion of said arm will at all times cover said opening, a manually operable member carried by said arm and projecting forwardly through said opening, suitable enclosing structure secured to the outer side of said door, spring latch mechanism for maintaining said structure in normal closed condition, a handle whereby said structure may be readily opened, and a nonfrangible transparent panel carried by said structure and so positioned and of such form as to enable said member to be readily viewed therethrough.

9. In an attachment for a signal box; a door having a rearwardly extending portion through which is provided an opening, an actuating arm pivotally connected to the rear side of said door, said arm so formed and arranged as to be suited for operative engagement with the clockwork starting levers of either of a plurality of types of signal boxes, a manually operable member carried by said arm and projecting forwardly through said opening, yielding means for maintaining said arm in normal position, suitable enclosing structure secured to the outer side of said door, spring latch mechanism for maintaining said structure in normal closed condition, a handle whereby said structure may be readily opened, and a nonfrangible transparent panel carried by said structure and so positioned and of such form as to enable said member to be readily viewed therethrough.

10. In an attachment for a signal box; a door having a rearwardly extending portion through which is provided an opening, an actuating arm pivotally connected to the rear side of said door, said arm so formed and arranged as to be suited for operative engagement with the clockwork starting levers of either of a plurality of types of signal boxes, a manually operable member carried by said arm and projecting forwardly through said opening, a stop for limiting the actuating movement of said arm, suit-

able enclosing structure secured to the outer side of said door, spring latch mechanism for maintaining said structure in normal closed condition, a handle whereby said structure may be readily opened, and a nonfrangible transparent panel carried by said structure and so positioned and of such form as to enable said member to be readily viewed therethrough.

11. In an attachment for a signal box; a door having a rearwardly extending portion through which is provided an opening, an actuating arm pivotally connected to the rear side of said door, said arm so formed and arranged as to be suited for operative engagement with the clockwork starting levers of either of a plurality of types of signal boxes, a manually operable member carried by said arm and projecting forwardly through said opening, yielding means for maintaining said arm in normal position, a stop for limiting the actuating movement of said arm, suitable enclosing structure secured to the outer side of said door, spring latch mechanism for maintaining said structure in normal closed condition, a handle whereby said structure may be readily opened, and a nonfrangible transparent panel carried by said structure and so positioned and of such form as to enable said member to be readily viewed therethrough.

12. In an attachment for a signal box; a door having a rearwardly extending portion through which is provided an opening, an actuating arm pivotally connected to the rear side of said door, said arm so formed and arranged as to be suited for operative engagement with the clockwork starting levers of either of a plurality of types of signal boxes and so that some portion of said arm will at all times cover said opening, a manually operable member carried by said arm and projecting forwardly through said opening, yielding means for maintaining said arm in normal position, a stop for limiting the actuating movement of said arm, suitable enclosing structure secured to the outer side of said door, spring latch mechanism for maintaining said structure in normal closed condition, a handle whereby said structure may be readily opened, and a nonfrangible transparent panel carried by said structure and so positioned and of such form as to enable said member to be readily viewed therethrough.

13. In an attachment for a signal box; a manually operable actuating member, a door associated with said member and having an opening therethrough for a projecting portion of said member, relative construction and arrangement of said member and said door whereby some portion of said member will at all times cover said opening, suitable enclosing structure for the pro-

- jecting portion of said member, said structure suitably secured to the outer side of said door and comprising a transparent panel so positioned and of such form as to enable said member to be readily viewed therethrough, spring latch mechanism for maintaining said structure in normal effective relationship to said member, and an operating handle carried by said structure.
14. In an attachment for a signal box; a manually operable actuating member, a door associated with said member and having an opening therethrough for a projecting portion of said member, relative construction and arrangement of said member and said door whereby some portion of said member will at all times cover said opening, suitable enclosing structure for the projecting portion of said member, said structure suitably secured to the outer side of said door and comprising a nonfrangible transparent panel so positioned and of such form as to enable said member to be readily viewed therethrough, spring latch mechanism for maintaining said structure in normal effective relationship to said member, and an operating handle carried by said structure.
15. In an attachment for a signal box; a manually operable actuating member, a door associated with said member and having an opening therethrough for a projecting portion of said member, relative construction and arrangement of said member and said door whereby some portion of said member will at all times cover said opening, suitable enclosing structure for the projecting portion of said member, said structure hinged to the outer side of said door and comprising a nonfrangible transparent panel so positioned and of such form as to enable said member to be readily viewed therethrough, spring latch mechanism for maintaining said structure in normal effective relationship to said member, and an operating handle carried by said structure.
16. In an attachment for a signal box; a door having an opening therethrough, an actuating arm pivotally connected to the rear side of said door, said arm so formed and arranged as to be suited for operative engagement with the clockwork starting levers of either of a plurality of types of signal boxes, a manually operable member carried by said arm and projecting forwardly through said opening, a stop for limiting the actuating movement of said arm, suitable enclosing structure secured to the outer side of said door, spring latch mechanism for maintaining said structure in normal closed condition, a handle whereby said structure may be readily opened, and a nonfrangible transparent panel carried by said structure and so positioned and of such form as to enable said member to be readily viewed therethrough.
17. In attachment for a signal box; a door having an opening therethrough, an actuating arm pivotally connected to the rear side of said door, said arm so formed and arranged as to be suited for operative engagement with the clockwork starting levers of either of a plurality of types of signal boxes and so that some portion of said arm will at all times cover said opening, a manually operable member carried by said arm and projecting forwardly through said opening, suitable enclosing structure secured to the outer side of said door, spring latch mechanism for maintaining said structure in normal closed condition, a handle whereby said structure may be readily opened, and a nonfrangible transparent panel carried by said structure and so positioned and of such form as to enable said member to be readily viewed therethrough.
18. In an attachment for a signal box; a door having an opening therethrough, an actuating arm pivotally connected to the rear side of said door, said arm so formed and arranged as to be suited for operative engagement with the clockwork starting levers of either of a plurality of types of signal boxes, a manually operable member carried by said arm and projecting forwardly through said opening, yielding means for maintaining said arm in normal position, suitable enclosing structure secured to the outer side of said door, spring latch mechanism for maintaining said structure in normal closed condition, a handle whereby said structure may be readily opened, and a nonfrangible transparent panel carried by said structure and so positioned and of such form as to enable said member to be readily viewed therethrough.
19. In an attachment for a signal box; a door having an opening therethrough, an actuating arm pivotally connected to the rear side of said door, said arm so formed and arranged as to be suited for operative engagement with the clockwork starting levers of either of a plurality of types of signal boxes, a manually operable member carried by said arm and projecting forwardly through said opening, a stop for limiting the actuating movement of said arm, suitable enclosing structure secured to the outer side of said door, spring latch mechanism for maintaining said structure in normal closed condition, a handle whereby said structure may be readily opened, and a non-frangible transparent panel carried by said structure and so positioned and of such form as to enable said member to be readily viewed therethrough.
20. In an attachment for a signal box; a door having an opening therethrough, an actuating arm pivotally connected to the rear side of said door, said arm so formed

and arranged as to be suited for operative engagement with the clockwork starting levers of either of a plurality of types of signal boxes, a manually operable member 5 carried by said arm and projecting forwardly through said opening, yielding means for maintaining said arm in normal position, a stop for limiting the actuating movement of said arm, suitable enclosing 10 structure secured to the outer side of said door, spring latch mechanism for maintaining said structure in normal closed condition, a handle whereby said structure may be readily opened, and a nonfrangible trans- 15 parent panel carried by said structure and so positioned and of such form as to enable said member to be readily viewed there- through.

21. In an attachment for a signal box; a 20 door having an opening therethrough, an actuating arm pivotally connected to the rear side of said door, said arm so formed and ar-

ranged as to be suited for operative engagement with the clockwork starting levers of either of a plurality of types of signal boxes 25 and so that some portion of said arm will at all times cover said opening, a manually operable member carried by said arm and projecting forwardly through said opening, yielding means for maintaining said arm in 30 normal position, a stop for limiting the actuating movement of said arm, suitable enclosing structure secured to the outer side of said door, spring latch mechanism for maintaining said structure in normal closed condition, a handle whereby said structure may be readily opened, and a nonfrangible trans- 35 parent panel carried by said structure and so positioned and of such form as to enable said member to be readily viewed there- 40 through.

In witness whereof, I hereunto subscribe my name, this 22d day of December, 1922.

GEORGE ALFRED JACKSON.
